UNITED STATES PATENT OFFICE.

THOMAS D. MILLEA, JOHN D. MILLEA, MICHAEL J. CARROLL, AND EDWARD J. CARROLL, OF SPRINGFIELD, MASSACHUSETTS, ASSIGNORS TO CONSOLIDATED ENGINE STOP COMPANY, OF NEW YORK, N. Y., A CORPORATION OF CONNECTICUT.

SPEED-INDICATING DEVICE.

SPECIFICATION forming part of Letters Patent No. 732,953, dated July 7, 1903.

Application filed August 30, 1901. Serial No. 73,800. (No model.)

To all whom it may concern:

Be it known that we, THOMAS D. MILLEA, JOHN D. MILLEA, MICHAEL J. CARROLL, and EDWARD J. CARROLL, all citizens of the United States of America, residing at Springfield, in the county of Hampden and State of Massachusetts, have invented a new and useful Speed Indicating and Limiting Device, of which the following is a specification.

10 Our invention relates to speed indicating and limiting devices for motors, shafts, and machines in which certain peculiarly constructed and arranged mechanism is employed to move a pointer over a dial or into conjunction with an electrical contact-point, the dial and contact-point entering into said invention as important elements thereof, all as hereinafter fully described, and especially pointed out in the claims; and the objects of 15 our improvement are, first, to provide a device by which the speed of a motor, shaft, or machine may be accurately indicated, and, second, to provide a device by which a suitable stopping or regulating appliance may be 20 put in operation, whereby said motor, shaft, or machine may be stopped or have its speed limited or regulated. We attain these objects by the mechanism illustrated in the accompanying drawing, in which the preferred form 25 of construction of our device is illustrated by a perspective view.

Similar letters refer to similar parts throughout.

In the construction of our device a suitable 30 support is provided, which may be of any convenient form; but we prefer to use a case *a*, mounted on a standard *t* and provided with a door *b*. A shaft *c* is journaled in the case *a* by means of suitable bearings, and collars 35 or other similar devices are employed to prevent longitudinal movement of said shaft, one of such collars being seen at *s* in the drawing.

Mounted on the shaft *c* is a collar *d*, which 40 is adapted to slide longitudinally on said shaft, but is restrained from rotating thereon, a feather or any other of the well-known means adapted to bring about this result and applicable in this device being employed. A

collar *e* is tight on the shaft *c* remote from the collar *d* and has the arms *f* pivotally connected therewith, to the outer ends of which are affixed the governor-balls *g*. Other arms *h* are pivoted to the end of the collar *d* adjacent to the collar *e* and also to the arms *f*. 50 It will now be understood, of course, that when the shaft *c* is revolved rapidly the balls *g* will describe a circle of larger diameter than if said shaft is rotated slowly, provided means be employed to constantly tend to draw 55 said balls nearer the shaft. For the purpose of tensioning or drawing the balls toward the shaft we prefer to employ a weight, although a spring may be used instead, but will not give the desired accuracy, yet in many instances it can be substituted for the weight with good results. In this instance the weight *k* is suspended from an arm *j*, which is rigidly attached to a stud *i*. The stud *i* is free 60 to rotate so far as may be required, and the 65 pointer *l* or a rod upon which the pointer is mounted projects through said stud, with its lower end entering an annular recess *u* in the collar *d*. A dial *m* is preferably mounted on the case *a*, and the pointer *l* extends 70 upward through a conveniently-arranged slot in said case to a position where it is in 75 operative relation with the dial-face.

From the foregoing description it will be readily seen that the constant tendency of the weight *k* is to depress the arm *j*, and thus 80 rotate the stud *i*, so as to carry the lower end of the pointer *l* away from the governor-balls, and with it the collar *d*, which in turn draws 85 said balls toward the shaft *c* through the medium of the arms *h*. The extent of power exerted in this manner depends upon the location of the weight with reference to the stud, the amount of leverage being thereby varied, so that if said weight be moved away 90 from said stud it will exert a greater force tending to rotate the stud in a direction to carry the lower end of the pointer *l* to the right than when the weight is brought nearer the stud.

95 A belt is carried from any convenient part of the motor, shaft, or machine the speed of which it is desired to indicate to the pulley

- r on the outer end of the shaft c, whereby the latter is caused to revolve, and the weight k is moved toward or away from the stud i until in a position to properly indicate the desired normal speed through the medium of the pointer l and the dial m, when the parts are secured in place by set-screws or other convenient fastening means. Now when the speed of the motor, shaft, or machine varies by becoming greater or less than the normal or usual desired speed the upper end of the pointer l will be actuated to the right or left accordingly to indicate such variation on the dial m, because an increase in speed causes the governor-balls to fly out or away from the shaft c, and thus carry the sleeve d with the engaging end of said pointer to the left, which moves the upper end thereof in the opposite direction, the weight being lifted at this time, and a decrease in speed permits said weight to operate on said pointer and sleeve, the lower end of the former forcing the latter to the right, which draws said balls inward toward said shaft, while the upper end of the pointer moves to the left on the dial. Since the dial m is suitably marked, the position of the adjacent end of the pointer l shows at a glance whether or not the speed is normal and, if not normal, what is the amount of variation.
- For the purpose of shutting down the motor or machine when its speed exceeds a certain predetermined limit an adjustable contact-point n is located on the dial m or elsewhere in the path of travel of the pointer l. The contact-point n should be rendered adjustable through some suitable agency, so that it may be moved toward or from the pointer l when in its normal position in order to meet the requirements of different speed limits. The contact-point n is in electrical connection through the wires o and p with any of the well-known electrically-operated stopping devices for engines or motors. Hence when the pointer l engages said contact-point a circuit is made and the stopping device set in operation to shut down the motor. This cannot take place, however, until the increased speed causes the governor-balls to increase the distance between the shaft c and themselves and in turn to operate upon the pointer l through the medium of the intervening mechanism in the manner hereinbefore described.
- This device may also be electrically connected with any of the well-known checking apparatuses and such an apparatus set in operation when the pointer comes in contact with the point n to limit the speed of the motor in the usual manner. Thus it will be seen that this device may be used to stop or limit the speed of a motor, as well as to accurately indicate the rate of such speed.
- We prefer that the shaft be placed horizontally; but it will be easily understood how the shaft may stand vertically with the other members arranged in operative connection therewith to produce the same results without departing from the nature of our invention.
- What we claim as our invention, and desire to secure by Letters Patent, is—
1. The combination, in a device of the class named, of a shaft and a grooved sleeve slidably mounted thereon, governor-balls mounted on said shaft, pivotal connections between said balls and sleeve, a rotary stud having an arm extending therefrom at an angle thereto, a weight hung on said arm, and a pointer directly attached to and movable with said stud with the base of said pointer engaging the groove in the slideable sleeve, substantially as shown and described. 75
  2. The combination, in a device of the class named, of a shaft and a grooved sleeve slidably mounted thereon, governor-balls mounted on said shaft, pivotal connections between said balls and sleeve, a rotary stud having an arm extending therefrom at an angle thereto, a weight hung on said arm, a pointer or contact member attached to and movable with said stud with the base of said member engaging the groove in the sleeve, and an electrical contact-point in the path of travel of the contact member, substantially as shown and described. 80
  3. The combination, in a device of the class named, of a shaft carrying a sliding sleeve, governor-balls mounted on said shaft and operatively connected with said sleeve, a rotary stud provided with an arm, an adjustable weight mounted on said arm, a pointer or contact member passing through said stud into engagement with the sleeve, and an adjustable electrical contact-point in the path of travel of said contact member, substantially as set forth. 90
- In testimony whereof we have signed our names to this specification in the presence of two subscribing witnesses.
